URINAL BAG

Thomas J. Conway and Alexander W. Keema,
Wickford, R. I.

Application May 31, 1956, Serial No. 588,402

12 Claims. (Cl. 128—295)

This invention relates to a urinal bag for use by a male person who is unable to control the evacuation of his urine.

One of the objects of the invention is to provide a bag which is so constructed that it may be secured to the person in such a way as to prevent leakage about the juncture of the bag with the person.

Another object of the invention is to provide for comfortably positioning of the upper end of the bag in contact with the person.

Another object of the invention is to provide an arrangement which will prevent the liquid from moving upwardly in the bag in case the bag is in an inclined position.

Another object of this invention is to provide an arrangement in the bag which will permit of disinfecting material being utilized to absorb and reduce any odors which might occur from the bag when in use.

Another object of the invention is to provide a harness for strapping the bag to the person with this harness arrangement so constructed as to minimize irritation to the person.

Another object of the invention is to provide a harness which may be easily stretched to be moved to one side of the rectum for evacuation thereof without the necessity of detaching any part of the harness.

Another object of the invention is to provide a means for securely attaching the harness to the bag so that rupture of the connected parts will not occur.

Another object of the invention is to provide a bag which may be evacuated from the lower end thereof so that an attachment may be provided at this lower end when the wearer is lying down in bed.

With these and other objects in view, the invention consists of certain novel features of construction, as will be more fully described, and particularly pointed out in the appended claims.

In the accompanying drawings:

Fig. 1 is an elevation showing the front of the person with the bag attached;

Fig. 2 is a rear view of the person, showing the bag attached and the harness in position;

Fig. 3 is a perspective view of the bag partly in section;

Fig. 4 is a sectional view through two of the straps at the upper end of the bag;

Fig. 5 is a sectional view of the diaphragm portion of the bag with the opposite ends thereof broken away.

In proceeding with this invention, we have provided a tubular waterproof receptacle provided with a rigid annulus at its upper end about which the waterproof material is turned inwardly with a disinfecting means located within the inwardly turned portion, and we have formed this receptacle in upper and lower sections with a diaphragm over which each of the sections telescopes and is bound by a clamp, thus providing upper and lower chambers. The chambers are connected by a lip-type valve, permitting relatively free passage of liquid in one direction but preventing passage in the other direction, while

2

there is also provided means for permitting air displaced by the liquid of the lower chamber to be exhausted therefrom into the upper chamber as the liquid moves from the upper to the lower chamber. A harness-like arrangement is provided for securing the bag to the person, with one of the straps passing over the left shoulder as shown in this illustration and a means extending about the right side of the person to hold the strap from slipping off the left shoulder, while additional straps extend about the waist to snugly draw the receptacle against the body with the penis of the male person extending thereinto. This harness has a rubber portion which extends through the crotch and will be elastic so it may be moved from the crotch for evacuation of the colon.

With reference to the drawings, 10 designates generally a tubular receptacle which is formed in two flexible sections 11 and 12, which sections telescope from top and bottom over a relatively rigid diaphragm 13 and are bound to this diaphragm by a clamp 14 of a resilient nature having ears 15 which are drawn together by some suitable tightening means similar to a hose clamp. The sections are of a waterproof flexible material conveniently rubber. By this arrangement, the upper section 11 provides an upper chamber 16 and a lower section 12 a lower chamber 17. The diaphragm is provided with an opening 18 beveled as at 19 at its upper end and extending through a boss 20 (Fig. 5) protruding downwardly into the lower chamber 17. This boss is enlarged as at 21 providing a rib-like formation over which an elastic control valve 22 is stretched to telescope. This control valve is made of rubber-like material, such as rubber or synthetic rubber, and comprises a tubular body section 24 having a lip discharge end 25, the inherent resilience of which will maintain the two lips snugly in engagement but will permit liquid to pass through the portion 24 when the weight of the liquid is applied thereto but would prevent liquid surrounding this portion 25 from the lower end from being passed through this control valve 22. This liquid may discharge through opening 18 from the upper chamber 16 to lower chamber 17 but can not return by this passage. A second opening 26 is provided through the diaphragm and in this opening there is a tube 27 which extends upwardly beyond the upper surface of the diaphragm and this tube maintains a passage from one chamber to the other at all times so air which is displaced by the movement of liquid from the upper chamber 16 to lower chamber 17 may be passed through this tube from the lower chamber to the upper chamber.

The lower end of the lower chamber 12 is provided with an end wall 28 having a conical portion 29 discharging into the threaded conduit 30, which is controlled by a hand valve 31 so liquid in the lower chamber may be withdrawn therefrom by manipulation of this valve and if desired a tube 32 may be telescoped on nozzle 33 for directing the liquid to the desired waste discharge. This wall is secured to the lower end of the lower tubular section 12 by a hose-type clamp 34 which is drawn together by some suitable means so as to secure the tube to the end wall.

At the upper end of the upper section 11 there is provided an annulus 35 which is of an arcuate cross section. The tube 11 is turned inwardly over this arched annulus 35 and is moulded so that it will terminate in a thin tapered portion 36 and substantially maintain this shape. Within this rolled-in portion of the tube there is provided a circular ring 37 of some gauze-like material which will be absorbent and carry a disinfectant to reduce any odors which may exist within the receptacle. This gauze or absorbent material 37 is easily detached from its position and replaced by a fresh ring. The inwardly rolled molded

portion 36 of the tube serves to maintain this gauze-like pad in place.

A harness arrangement is provided for drawing this receptacle snugly against the body with the penis of the male person extending through the inwardly turned end of the receptacle and by reason of the curved portion even though drawn tightly against the person is comfortable for wear. This harness arrangement comprises straps 38 and 39 on either side of the receptacle which are secured to the metal annulus 35 by a pair of rivets 40. These straps being such that they may extend about the waist of the wearer as shown in Fig. 1 and tied, snapped, or otherwise fastened at their ends snugly about the waist. A shoulder strap is similarly secured to this annulus and comprises in the front a strap portion which may be of woven cotton material 41, while in the back there is a strap 42 of rubber. This strap 42 being of a sufficient length to pass through the crotch of the wearer and extend up the back to about waist line as shown in Fig. 2. The other portion of the shoulder strap which connects these two portions 41 and 42 is designated 43 and is of a length to extend over the shoulder and be secured to the front strap 41 by an S-shaped hook 42' passing through eyes in the strap 41 and in the strap 43 while in the rear the strap 42 is secured to the other end of the strap 43 by a tape, such as a lacing member, 44 passing through the eyes of the two parts and being tied together. In order to prevent the shoulder strap shown as extending over the left shoulder of the person in Figs. 1 and 2 from sliding off the left shoulder, strap 45 is provided extending about the right side of the person from hook 42' to the tie 44 so as to retain this strap from slipping from the shoulder. Should it be desired to remove the rubber portion 43 from the crotch for evacuating the colon, it is merely necessary to pull the strap to the dotted line position for this purpose and is unnecessary to detach any part of the harness.

The bag is of a length to extend along the leg of the wearer, usually on the inner side of the leg, and may be strapped to the calf of the leg by hand 46 as shown in Figs. 1 and 2.

From the foregoing, it will be apparent we have provided a urinal bag which may be readily concealed beneath the clothing of the person wearing the same and one which may be comfortable to be worn, it being desired to be pointed out that the rubber portion which extends through the crotch does not cause irritation and may be easily stretched to be moved to one side when it becomes desirable. The bag further may be readily sanitized in use by the absorbent pad contained therein and the bag is also detachable in sections to be easily boiled or cleaned, which is necessary for sanitary purposes. The discharge of the urine into the upper chamber quickly passes by its own weight into the lower chamber and is trapped as it is collected therein, the lower chamber being of a sufficient size to require emptying usually not oftener than twice a day. Emptying being by a drain tube which may lead to a receptacle when the user is in bed.

We claim:

1. A urinal bag comprising an elongated tubular waterproof receptacle having a diaphragm intermediate the ends of the receptacle providing upper and lower chambers, said diaphragm having openings therein, one of said openings being arranged for the passage of liquid from the upper to the lower chambers, a lip valve constructed

to permit passage of liquid in one direction only controlling the said opening and arranged for the flow of liquid from the upper to the lower chamber and a tube extending upwardly from another one of said openings to a height to prevent liquid passing therethrough for the passage of air from the lower to the upper chamber as displaced by said liquid.

2. A urinal bag as in claim 1 wherein said diaphragm has a boss with an opening therethrough extending downwardly in extension of said valve controlled opening and said valve is telescoped onto said boss.

3. A urinal bag comprising an elongated tubular receptacle having a functionally rigid annulus at one end with waterproof material embracing said annulus and turned inwardly through the opening in said annulus and back upon itself to provide a retaining pocket and a removable member carrying disinfectant held in said pocket by said turned edge end.

4. A urinal bag as in claim 3 wherein the removable member is an annular pad.

5. A urinal bag as in claim 3 wherein the annulus is arc shaped in radial cross section.

6. A urinal bag as in claim 3 wherein the annulus is arc shaped in radial cross section and the removable member is an annular absorbent pad of circular cross section fitting the arc shape of said ring.

7. A urinal bag comprising an elongated tubular receptacle having a functionally rigid annulus at one end with waterproof material embracing said annulus and turned inwardly through the opening in said annulus and straps secured through said material and annulus for holding the bag to the body.

8. A urinal bag comprising an elongated tubular waterproof receptacle, a strap secured to the front and back of the upper end of the receptacle of a length to extend from the front over the shoulder of the wearer and thence through the crotch to the back of the receptacle, said strap having an elastic portion extending through the crotch.

9. A urinal bag as in claim 8 wherein the elastic portion is of rubber-like material.

10. A urinal bag as in claim 8 wherein a second strap extends laterally about the body to the first strap at locations above the attachment of the first strap to the bag.

11. A urinal bag as in claim 8 wherein additional straps extend from the upper part of the receptacle about the waist of the wearer.

12. A urinal bag as in claim 8 wherein a second strap extends laterally about the body to the first strap at locations above the attachment of the first strap to the bag wherein additional straps extend from the upper part of the receptacle about the waist of the wearer.
